Attorney, Agent, or Firm—Nixon & Vanderhye**[57] CLAIM**

The ornamental design for a front shoe sole, as shown and described.

DESCRIPTION

FIG. 1 is a left side elevation view of a front shoe sole showing my new design in a position of use; The broken line showing of the shoe in FIG. 1 is for illustrative purposes only and forms no part of the claimed design.

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a perspective view thereof.
